FRANKLIN C. NELSON INVENTOR

BY *W. E. Currie*
ATTORNEY

UNITED STATES PATENT OFFICE

FRANKLIN C. NELSON, OF ELIZABETH, NEW JERSEY, ASSIGNOR TO STANCO, INCORPORATED, A CORPORATION OF DELAWARE

MULTIPLE SIPHON TUBE FOR SPRAYERS

Application filed August 13, 1929. Serial No. 385,540.

This invention relates to an improved construction of spraying device.

Spraying devices as customarily constructed are provided with one or more suction tubes through which liquid is adapted to be drawn from a reservoir into position to be struck by a blast of air and atomized into the form of spray. It is an object of this invention to provide a construction of suction tubing which shall be of increased efficiency, of a high degree of strength and with the elements thereof maintained in permanent adjustment.

Other objects will be apparent from the specification and from the accompanying drawings in which

Fig. 1 is a front elevation of a spraying device with parts broken away,

Fig. 2 is a section taken along the line II—II of Fig. 1,

Fig. 3 is a transverse section taken along the line III—III of Fig. 1 through the suction tubing, and

Fig. 4 is a transverse section taken along the line IV—IV of Fig. 1 through the suction tubing.

Referring particularly to the drawings, in its preferred embodiment, the device comprises a gas supplying means or compressor including a barrel 1, a piston head 2, a piston rod 3, and a handle 4. A plurality of blast openings 5 are provided in the head of the barrel. A reservoir 6 is rigidly associated with the barrel 1.

A tubular structure is provided for conducting liquid from the reservoir into position to be struck by a blast of air issuing from the blast openings 5. The tubular structure comprises a plurality of tubes 7, connected by webs 8, and having fluid communication with a tubular main or body portion 9. The tubular structure is rigidly secured to the head of the barrel 1 by means of solder or the like. It is positioned with the main 9, extending into the reservoir 6 and terminating adjacent the bottom thereof in position to be submerged in liquid introduced into the reservoir. The tubes 7 lie with their discharge ends terminating exteriorly of and adjoining the blast openings. In the embodiment illustrated, the main or body portion 9 is provided with a bore of generally oval shape in cross-section and the tubes 7 are provided with a bore of smaller diameter, generally cylindrical in shape.

In utilizing the device any suitable liquid is introduced into the reservoir 6. The piston is actuated to cause a blast of compressed air or the like, to be ejected through the blast openings 5 of the barrel. The blast of air passes across the delivery ends of the tubes 7 and creates suction in the tubular structure sufficient to draw a column of liquid from the reservoir 6 into position to be struck by the blast of air and broken into small particles, which are projected forwardly by the blast of air in the form of spray.

The tubular structure in the embodiment illustrated is constructed of a single strip of metal a portion of which is stamped to form the tubes 7 and connecting webs 8. The contacting portions of the structure are secured by solder or otherwise. It will be understood that the tubular structure can be formed in any other suitable manner; for example the tubes 7 can be formed separately from the body portion 9 and secured thereto by soldering or in any other suitable manner.

The unitary construction of suction tube described is possessed of a high degree of strength and is resistent to forces tending to dislocate the same. The constituent tubes constituting the suction tubing are accurately spaced and permanently maintained in adjusted position. The greater portion of the suction tubing constituted by the main or body portion is of enlarged bore by reason of which the likelihood of the suction tubing clogging with sediment is reduced to a minimum. The shape of the bore of the suction tubing permits liquid to be drawn therethru in a thin column and easily broken into a fine spray with a minimum of air volume and pressure.

While a preferred embodiment of the invention has been shown and described, it will be understood that various modifications can be made therein within the spirit and scope of the invention and such modifica-

tions are intended to be covered by the appended claims.

I claim:

- 5 1. In combination with a sprayer having a plurality of blast openings, a liquid delivery device mounted on the sprayer and comprising a single strip of metal shaped into the form of a flattened tube the upper end of which is crimped into a plurality of narrow
- 10 10 tubes, each terminating adjacent one of the blast openings.
- 15 2. In combination with a sprayer of the type in which the liquid to be sprayed is contained in a reservoir surmounted by a pump in communication with a plurality of blast openings, a flattened liquid delivery tube formed of a single sheet of metal rigidly secured on the sprayer and extending with its lower end into the reservoir, the upper end of
- 20 20 said flattened delivery tube being crimped into a plurality of small tubes, each of the tubes terminating adjacent one of the blast openings.

FRANKLIN C. NELSON.
